FRANK H. SCARDEFIELD, OF BROOKLYN, NEW YORK.

GOLD-BEATING MACHINE.

1,246,168.

Specification of Letters Patent. Patented Nov. 13, 1917.

Application filed April 27, 1916. Serial No. 93,853.

To all whom it may concern:

Be it known that I, FRANK H. SCARDEFIELD, a citizen of the United States, residing in the borough of Brooklyn, city of New York, in the county of Kings and State of New York, have invented certain new and useful Improvements in Gold-Beating Machines, of which the following is a specification, reference being had therein to the accompanying drawing.

This invention relates to a machine for beating or hammering gold and similar metals into thin sheets for various uses in the arts. The industry known as the gold beating industry, in which this machine is to be employed, ordinarily performs its work by hand through the use of large mallets or hammers which beat bold bars or sheets of certain size and thickness until they are reduced to very thin sheets, the beating being performed by a series of processes, each one of which leaves the sheet much thinner than before, and after each such process, the sheet being cut and the beating continued until the final result consists of leaves which are extremely thin and are adapted to be applied to manifold uses in an infinite number of applications in the scientific arts. The object of my invention is to provide improved mechanical means for doing the same work in a highly efficient and successful way. The invention, therefore, may be said to consist essentially in the construction, arrangement, and combination of the various parts, substantially as will be hereinafter described and then more particularly pointed out in the claims.

In the accompanying drawing illustrating my invention:

Fig. 1 is a vertical sectional side elevation of my improved gold beating machine;

Fig. 2 is a top plan view of the same;

Fig. 3 is an enlarged detail plan view of the horizontal cam which guides the lever age devices for positioning the molds or work tables;

Fig. 4 is a detail cross-section on line 4, 4 of Fig. 1.

Similar characters of reference designate corresponding parts throughout the different figures of the drawing.

The frame of the machine consists essentially of a cylinder or turret 1 of greater or less height and diameter and designed to rest firmly upon a flat or other surface which will give it a firm foundation. At the center of the cylinder 1 is a vertical socket 2 which connects with the wall of the cylinder 1 by four or more webs 3 (or any other number), all these parts being preferably cast integral with each other so that they may be surely and firmly combined together. In the socket 2 is a vertical standard 4 held stationary in said socket and provided at its upper end with a fork 5 in which is journaled a horizontal shaft 6 that carries the double hammer device 7 having hammer heads 7^a at each end and operating after the manner of a walking beam so that the blows may be alternately struck by the heads 7^a, there being also journaled in the upper fork 5 a drive shaft 8 having thereon a crank 9 which is pivoted at 10 to a connecting rod 11, the other end of which is pivoted at 12 to the hammer 7 at a point on one side of its fulcrum 6 at a suitable distance from said fulcrum. The connecting rod 11 preferably consists of two sections connected together by a spring 13 which surrounds and is attached to the two sections and which permits of each hammer having an elastic rebound after each stroke. The shaft 8 carries a drive pulley 14 and also a bevel pinion 15, the latter meshing with the horizontal bevel gear wheel 16 secured upon a casting 17 which surrounds the standard 4, there being a bushing or sleeve 18 between the casting 17 and the standard 4 so that by this combination it will be seen that while the shaft 8 is actuating the hammer it will be also imparting a horizontal rotative movement to the central casting 17.

The central member 17 carries a series of radial projecting arms 19 formed integral with or securely fastened to a circular bed 20 mounted upon the top periphery 21 of the turret 1, said bed 20 having a flange 22 which fits against the inside edge of the periphery 21 so that as the member 17 revolves carrying with it the radial arms 19, the bed 20 will be caused to rotate on the turret 1 which upholds it.

The various radial arms 19 are preferably slotted at 23 to permit levers 24 to project therethrough, said levers being pivoted at 25 to the arms 19 just below the slots 23 so that they may have a vibratory action in said slots, said levers 24 occupying a substantially vertically inclined position as indicated in Fig. 1. The function of the levers 24 is to impart a reciprocatory movement to a series of slides 26 to which they are pivoted, said slides 26 occupying a position radial in the turret 1 and being guided in their movements by guides 27 on the top of the rotary bed 20, it being obvious that these slides 26 move in and out toward the center of the machine across the face of the bed 20. The upper ends of the levers 24 are pivoted at 28 to the inner ends of the slides 26 or to some convenient point on the bottom of said slides where they project inwardly over the edge of the bed 20. In Fig. 1 at the right, one of these slides 26 is shown as working inside of its guides 27, while at the left a slide 26 is shown partly in section with the guide 27 removed so that the position of the slide 26 on the bed 20 can be more clearly perceived.

On top of each of the slides 26 is a circular disk 29 having a depressed recess 30 therein and provided on its periphery with ratchet teeth 31 so that said disk 29 is in effect a ratchet wheel. Each disk 29 is provided on its bottom at the center with a pin 32 which engages a perforation 33 in the slide 26 so that the disk 29 is susceptible of easy rotation on the pin 32. The recess 30 in each disk 29 carries a mold or form for the gold leaf which is preferably composed, according to the usual practice of the industry, of a multiplicity of skins 34, said skins being of any preferred kind or character and having the function of providing a beating mold possessed somewhat of resiliency and yet of sufficient hardness and toughness to enable the beating to be successfully performed thereon. The beating molds 34 are preferably square in form and are held in place by flat springs 35 or other equivalent devices which press against the sides of the square molds 34, all as clearly shown in Fig. 2. Associated with each one of the ratchet disks 29 is a pawl 36 adapted to engage the teeth 31 at times and to be disengaged therefrom at other times. These pawls are pivoted at 37 to the traveling bed 20 and are provided with springs 38 attached to one end of the pawl and also to the bed. The springs have the function of drawing the pawls toward the fixed pins 39 on the bed 20. When the pawl 36 is in its normal position, as shown with some of the pawls at the bottom of Fig. 2, it will be seen that the spring 38 holds the pawl against the pin 39, so that its tooth is in a position to engage the teeth 31 of the ratchet edge of the adjacent disk 29, so that

when said disk is moved radially toward the center of the machine by the inward reciprocation of the slide 26 which carries said disk, it will be obvious that the tooth of the ratchet 31 nearest to the pawl 36 will strike 70 against said pawl and will rotate said disk for a fraction of a revolution or until the movement of the slide 26 stops and it reverses its reciprocation, the effect of which reversal is to allow the teeth of the ratchet 75 31 to slip over the pawl until said disk reaches the other limit of its reciprocatory movement and stops and the pawl is allowed to resume its position in the path of the teeth so as to serve as an obstruction thereto and 80 cause the intermittent rotary movement of the mold to take place again when the slide again moves inwardly. The various positions of the pawls relatively to the different ratchets are shown in Fig. 2, and it will be 85 evident that each time a slide moves inwardly carrying with it one of the molds 34, said mold will be given a slight rotary shift which will change its position and consequently the position of the gold leaf resting thereon so that the hammer will strike it in a different spot after each change of 90 position.

The inner ends of the levers 24 are pivoted to horizontal links 40, each of which has on its inner end nearest the center of the machine a vertical downwardly-projecting pin 41 which engages the grooves in a horizontal fixed cam 42 which is secured in a stationary position to the central post 4, and which for convenience of construction rests upon the upper end of the central socket 2 which holds said post 4; and furthermore each link 40 is provided with an upwardly projecting pin 43 which connects by a spring 44 with a lug 100 or projection 45 on the underside of one or the other of the radial arms 19, these projections 45 being apertured in a suitable way to allow the passage through them of the links 40 and therefore serving as guides for said links 40. The springs 44 have the function of holding the pins 41 in the cam grooves. The latter, as shown in Fig. 3, which represents a plan view of this cam 42, are shown to consist of two such grooves 48 and 49 which are eccentric to the center of the cam and which connect by a right-angled cross-connecting groove 50 so that a pin, for example, in the groove 49, will travel around through such groove and then through groove 48 until 110 it reaches the shoulder 53 at the end of said groove, where it will be deflected at right angles and caused to pass through the cross groove 50 until it again reaches the inner groove 49 and begins to travel as before. Of course, there may be any number of these eccentric cam grooves, and I am not restricted to two, but may have three or four, and they may be arranged so that their paths 115 may have any degree of eccentricity provid- 120 125 130

ing only the result is achieved of so actuating the links 40 and the levers 24 as that said levers will vibrate the levers 24 during the revolution of the bed 20 and thus reciprocate the slides 26 with the required reciprocations to enable them to be constantly changing their position in order to change the position of the molds 34 and the surfaces of the gold leaf which is being exposed to the hammer's 10 blows and allow said blows to fall on all parts of such surfaces. The central member 17, which is a rotary member, is provided on its lower side with a circular flange 46 concentric with the center of the post 4, and this flange is engaged at certain times during the travel of the pins 41 through the cam grooves by the upwardly projecting pins 47, and this engagement restrains the movement of the pins at those moments when the pins 20 are opposite the cross groove 50 and thus counteracts the tendency of the springs 44 to throw the pins 41 out of the cam grooves and into the cross groove 50 at a time when this is not desirable. The function of the pins 47, 25 therefore, is to enable the guiding pins 41 to travel continuously around through the cam grooves until the end of the same is reached at the shoulder 53, at which time the pins 41 can enter the cross groove 50 and be shifted back to the beginning of their path of travel through said cam grooves. The way in which this action takes place will be understood when I say that on one of the webs 3 there is a vertical projection 51 having preferably an inclined end (see Fig. 4). On each of the links 40 there is a projection 52 preferably having an inclined edge. During the rotary movement of the bed 20 and the radial arms 19, carrying along at the 30 same time the links 40, it will be obvious that each time a projection 52 strikes against the projection 51, it will lift the lever 40, provided the lever is in such a position that the projection 51 is in the path of the projection 52. This happens when the pin 41 on said lever 40 is in the inner slot; that is to say, the slot 49, and is about to pass the cross slot 50, so that at this time the lever 40 is lifted, so as to cause the pin 47 to hang under the flange 46 and thus temporarily obstruct the action of the spring 44, which would pull the pin 41 into the cross slot 50; and thus the pin is allowed to pass on through the slot 49 and into slot 48, which it will do instead of dropping into the cross slot 50, as would be the case if the spring 44 acted at the intersection of these slots in the same way that it acts during the rest of the motion of the pin 41. Various differences in the size and relative arrangement of these colliding parts 51 and 52 may be made, as also in the arrangement of the pin 47 and the flange 46, and differences of adjustment and construction may be necessary if the cam slots were multiplied or 55 differently positioned, but all these lie within

the scope of my invention and may be changed to suit the object in view.

Furthermore, referring again to the hammer 7 and its heads 7^a, it will be noted that I preferably offset one half of the hammer from the axial line of the other half as shown in Fig. 2. The purpose of this is to allow the hammers to deal their blows upon the metal, which is being beaten, each time a mold carrying said metal comes under the hammer head, and by offsetting one of the hammer heads, the distance of travel for one of the molds to reach the point under the hammer is reduced without increasing the number of the molds, thus for example, 75 when there are eight of these molds, as shown in the present specimen of the invention, I am able to utilize more blows by this offset condition of one of the arms of the hammer heads, but I do not wish to be confined to this plan, but can if desired have both arms in rectilinear alinement with each other at the opposite ends of a straight walking beam, for the result will obviously be the same. 90

It will thus be understood in a consideration of the operation of the machine that the gold ribbon or leaf, or other metal which is being operated upon, will be subjected to a constant change of position in order that the blows of the hammer heads may fall thereon at different spots, or in different poses, a pose being the sequence of the blows. There are three principal movements of the molds or skin beds which carry the metal and on which the blows fall. First there is a revolving motion of the entire group of molds due to the rotation of the circular bed 20; then there is a radial reciprocatory motion for each mold due to the back and forth movement of each of the slides 26; then there is an intermittent individual rotary motion of each mold due to the action of the serrated disk and its pawl. By referring to one of the molds 34 in the lower left hand part of Fig. 2, there will be seen a plurality of poses at A, indicative of the points at which the blows of the hammers fall on the gold in beating the same. There will be precision and regularity in the layout of these poses, for as the bed 20 pursues a rotary path there will be rows of poses at which blows will be struck in such rotary path; as the slides 26 pursue reciprocatory paths these rows of poses will lie in radial lines; and as the serrated disks 29 rotate intermittently there will be radial rows of points on which the blows will be struck, so that taking a single mold 34 as an example, it will be seen that these rows 115 of poses will radiate from the center thereof in every direction. As the blows continue to be struck in such a large plurality of movements with such large diversity of poses which repeat in different ways an along all 130

these different lines, it necessarily follows that the metal is subjected to heavy beating in every part and repeated beating more accurately even than if it were being so operated upon by hammers wielded by the human arm with a much more regular operation and better result.

Many changes may be made in the exact construction and relative arrangement of the various parts of my machine to the end that it may be used in the most successful way in practice without exceeding the scope of the appended claims.

Having thus described my invention, what I claim as new and desire to secure by Letters Patent, is:

1. In a gold beating machine, the combination of a movable beating member, a circular series of mold carriers, and means for imparting to said mold carriers three motions relatively to the beating member, one of which is a revoluble motion of all of the mold carriers, another independent radial reciprocatory movement of each, and the third an individual rotation of each.

2. In a gold beating machine, the combination of a main frame, a horizontal rotary bed thereon, a beating member, means on which the beating member is fulcrumed, means for oscillating said beating member, and a group of mold carriers supported and moved by the bed, means for imparting to said carriers three motions, one of which is a group motion, another a radial reciprocation, and the third an individual rotation.

3. In a gold beating machine, the combination of a stationary frame, a horizontally rotating bed on said frame, means for imparting a rotary movement to said bed, a beating member, means central of the rotating frame on which the beating member is fulcrumed, and means for oscillating said beating member, together with mold carriers and lever devices for reciprocating them.

4. In a gold beating machine, the combination of a main frame, a bed rotating horizontally thereon, an oscillating hammer, means central of the revolving bed on which said hammer is fulcrumed, a plurality of supporting members for the metal to be beaten, said members being carried by the horizontally rotating bed, and means for radially reciprocating said supporting members.

5. In a gold beating machine, the combination of a main frame, a bed rotating horizontally thereon, a hammer device, means on which the latter is fulcrumed, and a plurality of supporting members for the gold or other metal to be beaten, said supporting members being carried by the horizontally revolving bed, an eccentrically grooved member for reciprocating said supporting

members, and means for imparting to said members an intermittent rotary motion.

6. In a gold beating machine, the combination of a main frame, a horizontally-rotating bed, means for rotating said bed, a vibrating hammer, means on which it is fulcrumed, a plurality of supporting members on which the gold to be beaten is placed, said members being carried by the rotating bed, and means for reciprocating said gold supporting members consisting essentially of a revolving cam and leverage connections between the same and the reciprocating devices.

7. In a gold beating machine, the combination of a main frame, an oscillating hammer, a vertical support in which the latter is fulcrumed, means for actuating the hammer, a plurality of supporting members for the gold to be beaten, means for imparting a horizontal rotary movement to the entire group of supporting members, means for reciprocating them individually radially of the machine, and means for individually rotating them intermittently so that the gold to be beaten may expose different points in poses to each blow of the hammer.

8. In a gold beating machine, the combination of a main frame, a plurality of resilient supporting members for the gold to be beaten, an oscillating hammer, means for supporting the latter so that its oscillations may be toward and away from the resilient supports, and an elastic shock device for taking care of the recoil of the hammer each time it strikes a resilient support.

9. In a gold beating machine, the combination of a plurality of mold carriers, a movable beating device, means for imparting to said mold carriers three motions relatively to the beating member, one of which is a revoluble motion of all of them, another an independent radial reciprocatory movement of each, and the third an individual rotation of each, cam-controlled levers for moving said mold carriers and detent devices for assisting in the control of the levers.

10. In a gold beating machine, the combination of a frame, a bed rotating horizontally thereon, a hammer device, a plurality of mold carriers supported on the rotating bed, means for radially reciprocating said molds, means for individually revolving them, said means including levers, and a cam provided with grooves which control the movement of said levers.

11. In a gold beating machine, the combination of a frame, a circular bed rotating horizontally thereon, an oscillating hammer, a plurality of mold carriers supported by the rotating bed and carried successively beneath the hammer, lever devices for reciprocating said mold carriers, and a cam

controlling the movement of said lever devices.

12. In a gold beating machine, the combination of a plurality of mold carriers, a beater, means for fulcruming the same centrally of the machine, means for carrying the plurality of mold carriers successively in a circular path beneath the action of the

hammer, means for radially reciprocating the mold carriers individually, and means for individually rotating the mold carriers, the latter being provided with ratchet and pawl devices. 10

In testimony whereof I affix my signature.

FRANK H. SCARDEFIELD.
